UNITED STATES PATENT OFFICE.

CARL BRAMMING, OF CHICAGO, ILLINOIS, ASSIGNOR TO ACCESSORIES MANUFACTURING CO., A CORPORATION OF ILLINOIS.

ELECTRIC CONNECTOR AND SWITCH.

1,320,834.

Specification of Letters Patent.

Patented Nov. 4, 1919.

Application filed May 3, 1917, Serial No. 166,235. Renewed August 8, 1919. Serial No. 316,203.

To all whom it may concern:

Be it known that I, CARL BRAMMING, a citizen of the United States, and resident of Chicago, county of Cook, and State of Illinois, have invented certain new and useful Improvements in Electric Connectors and Switches, of which the following is a specification and which are illustrated in the accompanying drawings, forming a part 10 thereof.

The invention relates to connectors especially adapted for use in automobile service, as for tail, cowl or spot lights, its object being to provide a simple, comparatively inexpensive and efficient connector which embodies means for conveniently closing and opening the circuit. The embodiment of the invention is hereinafter described and illustrated in the accompanying drawings in 20 which—

Figure 1 is a side elevation of the device, partly broken away,

Fig. 2 is a central longitudinal section thereof, showing the circuit as closed,

Fig. 3 is a similar view, showing the circuit open, and

Fig. 4 is a detail of the terminal and push member to which the line wire is attached.

At 10 there is shown a tubular socket open 30 at both ends and adapted to receive a plug connector 11, such as the base of an incandescent lamp, an ordinary bayonet joint being provided at 12 for securing the plug within the socket. The device is shown as 35 arranged for the use of a single line circuit, the plug 11 having a central contact element 13, adapted to coöperate with a spring-advanced plunger contact 14 telescopically fitting within a tube 15, extending through 40 a guide plate and an abutment 16 of insulating material. The plate 16 may be attached rigidly to the tube, or the latter may be merely provided with a shoulder 17 at its end serving as a limiting stop for the plate. 45 The plunger 14 is advanced by a spring 18 housed within it and reacting against the farther closed end of the tube 15.

A plunger, shown as in the form of a plate 19, of insulating material, loosely fits 50 upon the tube 15, and a spring 20 reacts between it and the plate 16. Instanding lugs, as 21, 22, struck in from the wall of the socket 10, and shown as located at its extreme end, limit the outward movement of

the plunger 19 under the influence of the 55 spring 20.

A metallic cap 23 telescopically fits over and slides upon the inner end of the socket member 10 and is centrally apertured to permit the entry of the line wire 24. A 60 plate of insulating material, 25, is seated within the cap 23, and while loosely engaging it is without movement in service. Extending through and attached to the plate 25 is a contact element 26, apertured at its 65 rearward end to receive and hold the end of the leading-in wire, its inner end coöperating with the closed end of the tube 15, these two elements constituting a pair of switch terminals. A pair of rigid fingers 27, 28, 70 extend forwardly from the plate 25, and are of greater length than the contact element 26. For convenience of manufacture these fingers are formed of a single strip of metal bent to U form, its bowed portion being 75 apertured to fit upon the contact element 26, to which it is rigidly secured.

The cap 23 is removably attached to the socket 10 by a form of bayonet joint, comprising a pair of slots, as 29, formed in the 80 wall of the socket and each being provided at its outer end with an inwardly facing shoulder 30 and with an oblique channel 31 and a pair of studs, as 32, 33, projecting inwardly from the side wall of the cap and 85 being substantially longitudinally alined. The edge of the oblique portion 31 of the slot 29 which is remote from the shoulder 30 inclines in the opposite direction toward its inner end, as shown at 34. As the cap is applied to the socket the studs 32, 33, successively enter the oblique portion 31 of the slot, the forward stud being guided by the oblique edge 34 acting as a cam to turn the 90 cap and bring the studs into line with the shoulder 30. As the cap is applied to the socket the fingers 27, 28, advance the plunger plate 19, compressing the spring 20, the plunger sliding upon the tube 15 and the contact element 26 presently coming into engagement with its end and thus closing the 95 circuit. Pressure upon the cap being relieved, the rearward stud 33 engages the shoulder 30 and holds the cap against further outward movement, maintaining the 100 switch terminals in contact. In order to open the circuit the cap is slightly turned to 105 disengage the stud 33 from the shoulder 30,

whereupon the springs force it backwardly, this stud traveling through the oblique portion 31 of the slot and guiding the advance stud 32 into engagement with the stop shoulder, and thus preventing the complete separation of the parts. If desired bosses, as 35, 36, may be struck in on the body of the socket to limit the outward movement of the plate 16 when the plug 11 is removed.

10 When the device is used in connection with a lamp the socket 10 will be fixed. When it is used to carry a lamp upon a wall surface, such as the cowl of an automobile, the cap 23 may be fixed.

15 While the preferred embodiment of the invention is illustrated and described, changes of detail may be made without departing from its scope, as, for example, the form of the pusher element interposed between the cap and the plunger 19, herein shown as a pair of fingers.

20 The particular form of bayonet joint for holding the cap in two positions is not material, though that shown is efficient and 25 satisfactory.

I claim as my invention—

1. In a combined electric connector and switch, in combination, two telescopically

associated and relatively slidable tubular members, one thereof forming a socket for receiving a connector plug and the other having a terminal for a leading-in wire, a telescopic spring-extended connector element within the socket member co-operative with a connector plug secured in the socket and with the leading-in wire terminal, a spring-retracted plunger slidable on the connector element, a pusher element within the tubular member having a leading-in wire terminal engageable with the plunger, and means for holding the terminal in two positions with reference to the socket element.

2. In a combined electric connector and switch, in combination, a socket for receiving a plug connector, a guide plate slidable in the socket, a tube extending through the guide plate, a spring-extended contact plunger telescopically carried by the tube, a spring-retracted plunger plate slidable on the tube, a cap slidable upon the socket, means for holding the cap in two positions, a line wire terminal carried by the cap and engageable with the end of the tube, and fingers carried by the cap for bearing on the plunger plate.

CARL BRAMMING.
